(57) **CLAIM**

The ornamental design for a bracket for a lighting fixture, as shown and described.

DESCRIPTION

FIG. 1 is a front perspective view depicting a bracket for a lighting fixture;

FIG. 2 is a front elevation view depicting the bracket of FIG. 1;

FIG. 3 is a rear elevation view depicting the bracket of FIG. 1;

FIG. 4 is a right side elevation view depicting the bracket of FIG. 1;

FIG. 5 is a left side elevation view depicting the bracket of FIG. 1;

FIG. 6 is a top plan view depicting the bracket of FIG. 1;

FIG. 7 is a bottom plan view depicting the bracket of FIG. 1; and,

FIG. 8 is a rear perspective view depicting the bracket of FIG. 1.

Any details shown in broken lines in the figures form no part of the claimed design of the bracket for a lighting fixture.
